FISH LURE

Bruce M. Liuska, 617 E. Brockton St.,
Madison Heights, Mich. 48071

Filed Sept. 9, 1968, Ser. No. 13,445

Term of patent 14 years

Int. Cl. D22—08

U.S. Cl. D22—28

FIG. 1

FIG. 2

FIG. 3

FIG. 4

FIG. 5

FIG. 1 is a side elevational view of my fish lure;
FIG. 2 is a top plan view of the lure shown in FIG. 1;
FIG. 3 is a bottom plan view of the lure shown in FIG. 1;

FIG. 4 is a front elevational view of the lure shown in FIG. 1; and

FIG. 5 is a rear elevational view of the lure shown in FIG. 1.

The dotted line showing of the hooks and eyes does not constitute part of my design.

I claim:

The ornamental design for a fish lure, as shown and described.
